Patented Jan. 24, 1922.

2 SHEETS—SHEET 2.

Inventor:
By his Attorney, William Novick, Geo. F. Mather

UNITED STATES PATENT OFFICE.

WILLIAM NOVICK, OF BROOKLYN, NEW YORK.

BATH APPLIANCE.

1,404,401.

Specification of Letters Patent. Patented Jan. 24, 1922.

Application filed March 5, 1921. Serial No. 449,663.

To all whom it may concern:

Be it known that I, WILLIAM Novick, a citizen of Russia, (having declared my intention of becoming a citizen of the United States,) and a resident of the borough of Brooklyn, county of Kings, city and State of New York, have invented certain new and useful Improvements in Bath Appliance, of which the following is a specification.

10 My invention is designed to afford a simple, inexpensive but effective and conveniently manipulatable bath appliance adapted for personal use, either in extended form for contactual engagement with the 15 rear portions of the body, or in folded form as a hand pad or flesh brush,—the invention consisting in the specific combination and arrangement of parts described and claimed,—and distinctive features being the 20 convertible character of the device, and its availability for the various functions incidental to the external cleansing and massage of the body, all as hereinafter more fully set forth.

25 In the accompanying drawings,

Fig. 1, is a view illustrating the use of my bath appliance in extended form for contact with the back of the bather;

30 Fig. 2, is a face view of the device as folded for use as a hand pad, or flesh brush;

35 Fig. 3, is a rear view of the device as folded for use as a hand pad or brush, the position of the hand in holding the same for manipulative purposes being indicated by dotted lines;

40 Fig. 4, is a view of the inner or face side of my bath appliance extended to its full length for use as indicated in Fig. 1;

45 Fig. 5, is a central longitudinal section thereof, taken upon plane of line 5—5, Fig. 4;

Fig. 6, is a medial sectional detail, upon a larger scale, taken upon the same central 45 longitudinal plane as Fig. 5;

Fig. 7, is a transverse section taken upon plane of line 7—7, Fig. 4, but on the same scale as Fig. 6.

50 The basic portion of my bath appliance consists of a strip B, of any suitable cloth or textile fabric, of one or more ply as may be found most expedient, according to the character and strength of the material used for the purpose, the edges being preferably 55 finished with a binding b, as indicated.

Positioned medially on the inner face of the basic strip B, is a pocket p, for holding a cake of soap s, and on each side of the soap pocket p, is a container c, c, for absorbent material a, a, (Figs. 5 and 6) such as natural or artifical sponge, or any equivalent porous material adapted to take up and hold moisture temporarily. The soap pocket p, and the containers c, c, are formed in whole or in part of textile netting or 60 gauze g, or the like, of sufficiently coarse weave or mesh to facilitate the ingress and egress of liquid.

The soap pocket p, is formed with a closable mouth p', (Fig. 7) which may be 70 secured to the basic strip B, by a button b', or equivalent means, for the purpose of retaining the soap in said pocket. Preferably a non-metallic button b', is used for the purpose, to avoid corrosion, etc.

75 The edges of the basic strip B, beyond the medial containers p, c, c, are preferably made convergent toward each end for neatness of appearance, and to facilitate manipulation.

80 Near each extremity thereof the said basic strip B, is formed with thumb loops b^x, b^x, for use as shown in Fig. 1, of the drawings.

h, is a hand-strap attached to the medial outer face of the basic strip B, to which 85 it is stitched at one edge, and may be secured at the other edge by means of the aforesaid button b', by which the mouth of the soap pocket p, is closed,—said button b', being attached to the mouth portion of said 90 pocket p, and extending through button holes in the basic strip B, and in the hand strap h, as indicated in Fig. 7.

When not extended for use as shown in Fig. 1, the portions of the basic strip B, beyond the medial compartments p, c, c, may be folded over the latter and tucked in under the strap h, adapting the device for use as a hand pad or flesh brush as indicated in Fig. 3.

100 The positon of the soap pocket p, centrally and between the containers c, c, of porous, absorbent material, insures an equal and economical distribution of soap to said absorbent material a, a, and to the surfaces 105 treated thereby.

110 The coarse netting or gauze g, not only makes an effectual face closure for the containing compartments p, c, c, but also acts as a skin abradant to promote circulation,

cleanliness, etc. In fact when used either in extended form as shown in Fig. 1, or as a hand brush or pad, as in Fig. 3, my device adapts itself to massage treatment of the 5 epidermis and flesh of the bather.

My appliance, while functioning for a plurality of purposes, is unitary in character, as well as simple, practical and sanitary in every respect, being washable like an ordinary towel. When equipped for use with soap as set forth the latter is always available in suitable relation to the other parts, and cannot be mislaid or lost.

The network or gauze *g*, used for the inner or contact face of the appliance not only protects the contents of the containers *p*, *c*, *c*, but also admits of the necessary percolation of liquid and soap solution therethrough, while the closer texture of the basic 20 strip *B*, acting as an outer shield or backing, prevents sprinkling and waste in that direction.

The foldable character of the appliance also adapts it for packing and transportation, a rubber bag being preferable for the purpose.

It is to be understood that by the terms netting or gauze (*g*) as herein used I mean to designate any suitable reticulated textile 30 fabrication having interstices of sufficient size or coarseness to function as and for the purpose herein set forth.

What I claim as my invention and desire to secure by Letters Patent is,

35 1. A bath appliance of the character designated, comprising an elongated backing strip of textile material, a reticulated fabric

secured to said backing strip to form a soap pocket, said fabric having spaced lines of stitching providing compartments for containing absorbent material upon either side of said soap pocket, and an auxiliary handle strap under which the ends of said backing strip may be folded.

2. A bath appliance of the character designated comprising an elongated backing strip of textile material, a reticulated fabric secured to said backing strip to form a soap pocket, said fabric having spaced lines of stitching providing compartments for containing absorbent material upon either side of said soap pocket, an auxiliary handle strap under which the ends of said backing strip may be folded, and unitary means for securing said handle and the flap of said 55 pocket to the backing strip.

3. A bath appliance of the character designated, comprising an elongated backing strip of textile material having medially a soap pocket and compartments containing 60 absorbent material on either side thereof, said pockets being faced with reticulated fabric, the back of said basic strip being formed with a transverse strap and the ends of said strip foldable in overlapped condition beneath said strap together with unitary means for detachably securing the mouth of said soap pocket and one end of said transverse back strap to said strip, for the purpose described.

WILLIAM NOVICK.
